LEWIS T. GODFREY.

UNITED STATES PATENT OFFICE.

HENRY BOOT, OF PHILADELPHIA, PENNSYLVANIA, ASSIGNOR TO THOMAS DOLAN & CO., OF SAME PLACE.

DESIGN FOR NUBIA.

Specification forming part of Design No. 6,777, dated July 22, 1873; application filed June 28, 1873.

B.

To all whom it may concern:

Be it known that I, HENRY Boot, of Philadelphia, Pennsylvania, have invented a Design for Nubia, of which the following is a specification:

The figure in the accompanying drawing represents sufficient of a nubia to illustrate my design, the principal feature of which is the peculiar groundwork or body A, which is of an open lace-like character, and has the waved and checkered appearance too clearly shown in the drawing to need description. Upon this ornamental body is a scalloped stripe or stripes, B, composed of coarse threads interlocked with those of the said body, and

at the edge of the nubia is a border, D, of the same character as the stripe B.

Irrespective of the colors employed, I claim—

1. The design for the body or groundwork A of the nubia, substantially as described and represented.

2. The design for the whole nubia, including the body A, stripe B, and border D.

In testimony whereof I have signed my name to this specification in the presence of two subscribing witnesses.

HENRY BOOT.
